UNITED STATES PATENT OFFICE.

GILBERT J. WHITE, OF OCEANSIDE, CALIFORNIA.

VALVE-LIFTER.

1,361,427.

Specification of Letters Patent. Patented Dec. 7, 1920.

Application filed June 22, 1920. Serial No. 390,761.

To all whom it may concern:

Be it known that I, GILBERT J. WHITE, a citizen of the United States, residing at Oceanside, in the county of San Diego, State 5 of California, have invented a new and useful Valve-Lifter; and I do hereby declare the following to be a full, clear, and exact description of the invention, such as will enable others skilled in the art to which it 10 appertains to make and use the same.

The invention relates to valve lifters and has for its object to provide a device of this character comprising a U-shaped member having its lower end provided with a foot 15 adapted to engage under the washer of the coiled spring carried by the valve stem and provided with a vertically slidable bar, the lower end of which engages a valve. Also to provide a lever whereby the slidable member 20 may be moved in a vertical plane downwardly for compressing the spring.

A further object is to provide a handle member provided with a pivoted dog which is spring actuated and which dog co-operates 25 with ratchet teeth on the vertical slidable member and forms means for holding the vertical slidable member in any position to which it may have been moved thereby holding the valve spring in compressed position.

30 A further object is to provide the lower end of the U-shaped member with spring arms, which normally spring apart, said arms being provided with horizontally disposed flanges for engaging under the valve stem washer, the spring arms allowing of 35 the reception of various sizes of valve stems therebetween. Also to provide a slidable collar on the lower end of the U-shaped member so that the spring arms may be 40 forced toward each other, and into close engagement to each other.

With the above and other objects in view the invention resides in the combination and arrangement of parts as hereinafter set 45 forth, shown in the drawings, described and claimed, it being understood that changes in the precise embodiment of the invention may be made within the scope of what is claimed without departing from the spirit 50 of the invention.—

In the drawings:—

Figure 1 is a side elevation of the valve-lifter showing the same applied to a conventional form of valve.

55 Fig. 2 is a vertical sectional view through the valve lifter showing the parts in position

they assume when the valve spring is compressed.

Fig. 3 is a front edge view of the valve spring lifter. 60

Fig. 4 is a perspective view of the bifurcated end of the U-shaped frame of the lifter. 65

Referring to the drawings the numeral 1 designates a U-shaped frame, the lower end 65 of which frame is bifurcated as at 2 so as to form spring arms 3 which normally are sprung apart. The outer ends of the spring arms 3 are provided with horizontal portions 4, the adjacent edges of which are provided 70 with recesses 5, which recesses receive the valve stem 6, when the valve lifter is in position. After the spring arms 3 have been properly positioned the collar 7 may be moved outwardly over the same so that they 75 will be contracted into engagement with the valve stem so that they will be prevented from displacement. The recesses 5 are shallow so that the pin 8 which is disposed beneath the washer 9 will pass between the 80 spring arms 3 when the U-shaped member is forced upwardly by the mechanism hereinafter set forth. Washer 9 engages the upper edges of the spring arms 3 and when forced upwardly contracts the coiled spring 85

10 which is interposed between the washer 9 and the engine casing 11. U-shaped member 1 has its horizontal arm 12 provided with a vertically disposed guide arm 13 and slidably mounted in bearings 14 of the arm 90 12 in the right angled arm 15 is a vertically movable bar 16, the lower end of which bar is preferably pointed and adapted to engage in the valve 16 carried by the valve stem 10. Valve 16 is normally held in engagement 95 with the valve seat by means of the coiled spring 10. Extending upwardly from the horizontal arm 15 is a handle member 18, which member is adapted to be grasped by the hand of the operator so that the device 100 as a whole may be steadied when the slidable bar 16 is being forced downwardly by the operating lever 19, which lever is bifurcated and has its arms pivotally connected as at 20 to the slidable bar 16, said lever being pivotally connected as at 21 to the upper end of a rockable link 22. Link 22 is bifurcated at its lower end and is pivotally connected as at 23 at its lower end to the horizontal arm 12. 105

It will be seen that when the lever 19 is moved upwardly in the direction of the arrow *a* shown in Fig. 1 that the vertical slid-

able bar 16 will not move but will be held in engagement with the valve 16, however the U-shaped frame 1 will be moved upwardly thereby compressing the valve spring 10 and 5 moving the washer 9 out of engagement with the pin 8, so that the pin 8 may be removed and if so desired the valve as a whole disassembled for grinding the valve seat or for any other purpose. U-shaped frame 1, as 10 it moves upwardly causes the arm 15 to also move upwardly and to hold the frame in any upward position to which it may have been moved, a pivoted pawl 24 is provided, which pawl is pivotally mounted as at 25 in an 15 aperture of the arm 15. The nose 26 of the pawl 24 ratchets over a series of ratchet teeth 27 carried on one edge of the slidable bar 16. The upward movement of the U-shaped member 1 being against the action of the 20 coiled valve spring 10, it will be seen that the pivoted pawl 24 will hold the frame in any position to which it may be moved. Pawl 24 is normally held with its nose 26 in engagement with the ratchet teeth 27 by means of 25 a coiled spring 28. Pivotally mounted on the handle 18 as at 29 is a hand grip member 30, which grip member has its finger engaging portion 31 disposed adjacent the handle so that it is within easy reach of the operator 30 at all times. The upper end 32 of the pawl 24 is disposed in a bifurcation of the member 30 and is adapted to be engaged by pins 33 which pass through the arms of the bifurcation and form means for engaging the 35 pawl end 32 for forcing the nose 26 into and out of engagement with the ratchet teeth 27.

From the above it will be seen that a valve spring compressing device is provided which device is so constructed that the lower end 40 of the U-shaped member which engages the valve stem will be guided in its upward movement and prevented from displacement and accidental release of the valve spring after the same has been compressed. It will 45 also be seen that an auxiliary handle is provided which may be grasped by the operator for steadyng a device when the lever 17

is being forced upwardly thereby additionally assuring the tool as a whole against displacement. By providing a spring actuated dog 24, the valve stem spring will be held automatically in any position to which it may have been moved upon release of the operating lever 19.

The invention having been set forth what 55 is claimed as new and useful is:—

A valve spring compressor and holding device comprising a U-shaped member, the lower end of said U-shaped member being provided with a bifurcated horizontal portion, the arms of said bifurcated portion being spring arms and normally sprung out, a slidable collar slidably mounted on the lower end of the U-shaped member and adapted to be forced over the spring arms for forcing the 60 same toward each other, flanges carried by the spring arms and provided with recesses adapted to receive opposite sides of the valve stem, a vertically disposed arm carried by the upper horizontal arm of the U-shaped 65 member and spaced from the end thereof, a bearing in the end of the upper horizontal member of the U-shaped member, a bearing carried by an arm at the upper end of the vertically disposed member carried by the 70 upper arm of the U-shaped member, a vertically slidable valve engaging bar slidable in said bearing, a lever carried by the U-shaped member for moving the slidable bar vertically, a handle member for steadyng the 75 valve spring lifter as a whole and a spring actuated detent for holding the vertically slidable bar in any position to which it may be moved, and also forming means for holding the valve spring in compressed condition.

In testimony whereof I have signed my name to this specification in the presence of two subscribing witnesses.

GILBERT J. WHITE.
